UNITED STATES PATENT OFFICE.

WILLIAM EDWIN SYKES, OF SLOUGH, ENGLAND.

MACHINE FOR CUTTING TOOTHED GEAR-WHEELS.

1,188,219.

Specification of Letters Patent. Patented June 20, 1916.

Application filed July 6, 1914. Serial No. 849,296.

To all whom it may concern:

Be it known that I, WILLIAM EDWIN SYKES, a subject of His Majesty the King of Great Britain, residing at Slough, in the 5 county of Buckingham, England, have invented a new and useful Improvement in Machines for Cutting Toothed Gear-Wheels, of which the following is a specification.

This invention relates to improvements in 10 machines for cutting toothed gear wheels and will be described with particular reference to a machine arranged for cutting double helical wheels though it may also be arranged for cutting straight toothed spur 15 wheels.

In the specification to Letters Patent, No. 1,103,831, dated July 14, 1914, I have described a machine according to which it is proposed to cut helical teeth by means of 20 two toothed disk or pinion shaped cutters, each adapted to turn within suitable bearings carried on a reciprocating or sliding carriage, each carriage being reciprocated so as to impart a planing or shaping action 25 to each cutter, by means of a separate crank, adjustable pin and connecting rod, the two cranks working respectively one from the right hand and the other from the left hand side of the wheel blank. Reference is also 30 made in the aforesaid specification to the difficulty of forming continuous double helical teeth by the aforesaid planing or shaping action of the cutters when advancing simultaneously from each face and meeting at 35 the apex of the teeth, owing to the cutters fouling each other directly, or by the chips cut from the blank gathering in the center, and means of avoiding some of the drawbacks were pointed out. It is stated in said 40 specification that the cutters need not advance simultaneously from each face and means are described for altering the relative positions of the cutters thereby producing a difference in time between the cutting 45 operations of the respective cutters.

According to the present invention it is proposed to dispense with one of the operating cranks and its reciprocating or sliding carriage above referred to, while at the same 50 time providing improved means for producing the difference in time required between the cutting operations of the two cutters. Both cutters may be driven from one crank, one cutter advancing as the other is with-

drawing, the generating feed mechanism being operated by any suitable means such as a pawl and ratchet. The driving crank and sliding carriage may be modified by using the well known square or oblong block on the crank pin arranged to slide in a slot in 60 the sliding carriage.

In the accompanying drawings which illustrate one embodiment of this invention:—Figure 1 is a plan of the machine. Fig. 2 is a side elevation. Fig. 3 is an end 65 elevation. Figs. 4, 5 and 6 are plan, side, and end elevations, respectively, of part of a machine, illustrating a modified form of feed mechanism, and, Figs. 7, 8 and 9, 10, and 11, 12, show three alternative constructions of part of a machine, in plan and elevation, respectively, for operating the generating mechanism.

In the drawings 1 is a saddle mounted on the bed 2.

3, 4, are bearings mounted on the saddle 1 to carry the revoluble head spindle 5. A mandrel 6 extends from the spindle 5, its outer end being journaled in the bearing 7 carried by the saddle 1. The mandrel 6 80 passes through a distance piece or chuck 8 and is arranged to carry the wheel blank 9 which represents the work to be done. For the purpose of holding the wheel blank in position a screw thread is formed on the 85 arbor 6 to receive a nut 10, a washer 11 being placed between the work and the nut.

The cutters 12, 13, are mounted on spindles revoluble in holders or boxes 14, 15, which are pivoted or hinged at 16, 17, to adjustable carriages 18, 19, mounted on the sliding carriage 92. Within the boxes 14, 15, and on the spindles carrying the cutters, are mounted double helical toothed pinions 20, 21 engaging with correspondingly toothed wheels 22, 23, mounted on the spindles 24, 25, each between the faces of bearings 26, 27, forming part of the adjustable carriages 18, 19. The spindles 24, 25 are extended beyond the bearings 26, 27 and such extended parts may be rifled or provided with a quick screw and be passed through bearings 28, 29 rigidly supported by the bed of the machine. Worm wheels 30 and 31, having projecting bosses are 105 revolubly mounted in the bearings 28, 29, through which worm wheels the spindles 24, 25 are adapted to slide.

The reciprocating or sliding carriage 92 is actuated by means of a crank plate 93 carrying a crank pin 94 having a block 95 mounted thereon. The block 95 is adapted to slide 5 in a vertically arranged slot 96 provided in the sliding carriage 92, or in an adjustable piece secured thereto. The crank pin 94 is mounted on the crank plate 93 in such a manner that it may be adjusted to increase 10 or decrease the throw and therefore the length of travel of the sliding carriage. The adjustment of the position of the carriage 18 or 19 on the sliding carriage 92 may be effected by slackening the bolts 97 or 98 and 15 moving the carriage 18 or 19 relatively to the carriage 92.

The crank plate 93 is mounted on a shaft 99 carrying a worm wheel 100 driven by a worm 101. The worm 101 is mounted on the 20 shaft 44 which also carries the driving pulley 45.

For the purpose of imparting a generating feed action to the cutters, and a rotative movement to the wheel blank, the worm 25 wheel shaft 99 is provided at its outer end with a crank disk 49 having an adjustable crank pin 50 which actuates, by means of connecting rod 51, ratchet wheel 52 mounted on shaft 53, on which a bevel wheel 54 is 30 mounted. A bevel wheel 55 intermeshes with bevel wheel 54 to drive, through the bevel wheels 56, 57, the shaft 58 and through the train of change wheels 59 and worm 60, 35 slidably mounted on the shaft 61, the worm wheel 62 which turns the spindle 5 and the wheel blank 9.

On the inner extremity of shaft 53, is keyed a spur wheel 83 engaging with a similar spur wheel 84, which is keyed to shaft 40 81 carrying worm 63 engaging with worm wheel 30. A further bevel wheel 80 is provided on shaft 53 adapted to intermesh with and drive bevel wheel 64 keyed on a shaft 65 which carries the bevel wheels 66 and 67. 45 The driven wheel 67 is keyed to shaft 68 which also carries a spur wheel 85 engaging with a similar spur wheel 86 keyed to a shaft 82 carrying a worm 69 engaging with worm wheel 31.

50 The generating feed mechanism acting on the cutter 13 may be thrown out of gear by means of the jaw clutch 74. The jaw clutch 74 also provides the means for adjusting the cutters independently of each other, each 55 part of the clutch being furnished with a hand wheel for this purpose.

The hand wheel 71 and the screw 72 working in a nut attached to the saddle 1, serve to move the saddle on its bed, thus adjusting 60 the saddle for various diameters of wheel blanks and also providing means for feeding the blanks against the cutters.

65 The action of the machine is as follows:— When the cutters and blank are secured in position, the position and stroke of the cut-

ters correctly adjusted and the desired change wheels 59 mounted, but the pawl kept out of engagement with the ratchet wheel 52, saddle 1 is moved until the desired depth of tooth is reached, then the ratchet 70 wheel 52 is put into operation. The cutters are rotated in one direction by the rifled bars 24, 25, during the cutting operation and in the reverse direction on the return or idle stroke, the result being that right 75 and left hand helical grooves are cut on the blank, and on every revolution of the crank disk 49 a generating feeding motion is imparted to the cutters and to the wheel blank. The ratio of the change gears 59 is chosen 80 so that the relative motion of the cutters 12, 13, and the wheel blank 9 is the same as that of a double helical spur gear wheel intermeshed with two single helical pinions represented by the wheel blank and cutters 85 respectively. It will therefore be seen that the machine works on the generating principle, and that when the wheel blank has made one revolution the work is complete, providing the work has been fed so far 90 against the cutters that the correct tooth depth is cut. If desirable for any particular class or size of work two or more separate cuts may be taken, that is to say, some fraction of the tooth depth may be cut on 95 the first revolution of the blank and the remaining depth on one or more subsequent revolutions of the blank.

While it has been found that the ratchet generating feed mechanism above described 100 for operating the generating mechanism is convenient, it will be apparent that such mechanism may consist of a belt drive from the driven worm shaft, and Figs. 4, 5 and 6 illustrate the essential parts of a machine 105 arranged with this form of drive. In these figures, 116 is the driving pulley mounted on the worm shaft 117, a second and smaller pulley 118 being keyed on the same shaft. A belt 119 connects the pulley 118 with a 110 pulley 120 keyed on the shaft 121, which is the equivalent of the shaft 65 of the machine shown in Fig. 1. Bevel wheels 122 and 123 engaging with bevel wheels 124 and 125, respectively, are keyed on said shaft and impart 115 generating feed to the cutters in a manner similar to that previously described. For the purpose of imparting the generating feed to the wheel blank, a spiral gear 126 is keyed on the shaft 121 adapted to 120 mesh with a spiral gear 127 mounted on a stud shaft 128 carried by the frame of the machine. The spiral gear 127 is connected to the shaft 129 (equivalent of shaft 58 in Fig. 1) by means of the gear wheels 130 and 131 and change wheels 132 and 133. It will further be obvious that the gear wheels 20, 21, 22 and 23 may be replaced by straight toothed wheels, as shown in Fig. 4, and that the helical trace may be imparted to the 130

cutters by other means than the rifled bars 24 and 25, and three alternative arrangements are illustrated in Figs. 7-12. In the construction shown in Figs. 7 and 8, the 5 helical trace is imparted to the cutters by a worm 134 and worm wheel 135 which correspond with the worm 63 and worm wheel 30 shown in Fig. 1. The worm wheel 135 is keyed on the end of a long worm 136 which, unlike the bar 24, has no axial movement. A spiral gear 137, mounted on the 10 cutter spindle, is adapted to gear with a spiral gear 138 keyed on a shaft 139 arranged at right angles to the cutter spindle 15 and worm 136, which shaft serves as a pivot for the tool-box. A worm wheel 140 is keyed on the shaft 139 which wheel is adapted to roll on the worm 136 which in turn will cause spiral gear 137 and the cutter 20 to revolve, or partially revolve, thereby imparting the desired helical trace to the cutters, providing the ratios of the various gear wheels have been suitably chosen. The generating feed is transmitted to the cutter 25 by worm wheel 135 through the parts 136, 140, 138 and 137, as will be readily understood. The arrangement illustrated in Figs. 9 and 10 operates in a similar manner to that shown in Figs. 7 and 8, but in this 30 case, a spiral member 136 is located in the same plane as the cutter spindle upon which is keyed a spiral gear 141 adapted to mesh with a spiral gear 142, the spindle 143 of which forms the pivot for the tool-box. The 35 spiral gear 142 is adapted to engage with and roll on the spiral member 136. In the arrangement illustrated in Figs. 11 and 12, a spiral gear 144 is mounted on the cutter spindle, which gear is adapted to engage 40 with a spiral gear 145 the spindle 146 of which forms the pivot for the tool-box. The spiral gear 145 also engages with a spiral gear 147 internally threaded and mounted on the rifled bar 148, on the outer end of 45 which is keyed the worm wheel 135 revolved by the worm 134, as previously described. When the worm wheel 135 is revolved, the rifled bar 148 having no axial movement, causes the spiral gear 147 to 50 travel thereon and revolve, which movement imparts the necessary movements to the cutter.

Means are preferably provided for moving the cutters away from the work on the 55 return or idle stroke, otherwise the cutters may be damaged, but this mechanism forms the subject matter of a further application for Letters Patent, Serial Number 849,297, filed July 6, 1914, and will not be further 60 referred to herein.

If one of the cutters is disconnected from the driving mechanism single helical or spiral wheels may be cut.

It will be understood that while the mechanism for imparting a reciprocating move-

ment to the sliding carriage 96 comprising the worm wheel 100 and its co-operating parts, is shown arranged in the center, it may if desired be arranged to one side or the other, as shown in Figs. 4, 5 and 6, the 70 position of the co-operating parts being modified accordingly.

With a machine arranged as above described it is possible by means of the pinion shaped cutters to cut continuous double 75 helical teeth of the true-generated outline up to that part of their apex where the right and left hand teeth meet, thus insuring the utmost strength of the teeth, economy of production as well as accuracy and efficiency 80 in the working of the gear wheels.

It will be obvious that straight toothed spur wheels may be cut on this machine by simply substituting pinion shaped cutters having straight teeth for the helical cutters 85 12, 13, and spindles 24, 25, which have a simple reciprocatory sliding movement in their bearings in place of a reciprocatory rotary movement as above described.

What I claim is:—

1. In a machine for generating and cutting toothed gear wheels, the combination of a bed, means carried thereon for axially mounting and turning the wheel blank to be operated on, a second bed, a carriage mounted thereon, means for imparting a reciprocating movement to said carriage in a plane parallel with the face of the wheel blank, a pair of cutters carried by said carriage, and means for driving said wheel 90 blank and said cutters simultaneously.

2. In a machine for generating and cutting toothed gear wheels, the combination of a slideable carriage, a pair of carriages rigidly yet adjustably mounted thereon, a 95 holder pivoted to each of said adjustable carriages, a revoluble shaft mounted in each of said holders, a pinion shaped cutter mounted on one end of each of said shafts, a pinion carried by each shaft, a bearing 100 formed on each of said adjustable carriages, spindles revolvably mounted therein, gear wheels mounted on said spindles and engaging with said pinions, a nut engaging with each of said spindles, and means for sliding 105 said spindles in said nuts.

3. In a machine for generating and cutting toothed gear wheels, the combination of a slideable carriage, a pair of carriages rigidly yet adjustably mounted thereon, a 110 holder pivoted to each of said adjustable carriages, a shaft revolvably mounted in each of said holders and carrying a pinion shaped cutter, a spindle revolvably mounted in each of said adjustable carriages, two engaging 115 gear wheels mounted, respectively, on said shafts and spindles, a nut engaging with and turning said spindles, gear wheels and cutters and means for imparting a reciproca- 120 tory movement to said slideable carriage.

4. In a machine for generating and cutting toothed gear wheels, the combination of a 50 slidable carriage, a pair of carriages rigidly yet adjustably carried thereby, a shaft 5 and a spindle revolvably mounted in each of said adjustable carriages, gear connections between said shafts and spindles for imparting rotary motion from the latter to the former, a cutter in the form of a pinion 10 mounted on each of said shafts, mechanism for imparting a generating feed action to said cutters, and a crank operatively connected with said slidable carriage to impart a reciprocatory movement thereto.
- 15 5. In a machine for generating and cutting toothed gear wheels, the combination of means for rotatably mounting a wheel blank on its axis, means for moving said wheel blank at right angles to its axis, a slidable 20 carriage, a pair of carriages rigidly yet adjustably carried thereby, a pinion shaped cutter mounted on each of said adjustable carriages, means for reciprocating said slidable carriage to and fro and feeding mechanism adapted to act upon said cutters 25 whereby they are revolved on their axes.
6. In a machine for generating and cutting toothed gear wheels, the combination of means for mounting and turning a wheel 30 blank on its axis, a carriage and means for sliding it with a shaping head action to and fro in a plane parallel with the axis of the wheel blank, a pair of carriages rigidly yet adjustably carried by said slidable carriage, 35 a pinion shaped cutter mounted on each of said adjustable carriages, means for feeding and withdrawing said wheel blank to and from said cutters, and change wheels and connecting mechanism for turning said 40 wheel blank when mounted concurrently with the reciprocating movement of said cutters.
7. In a machine for generating and cutting double helical or herring-bone toothed 45 gear wheels, the combination of a bed, means carried thereon for axially mounting and turning the wheel blank to be operated on, a second bed arranged lengthwise in a plane parallel with the axis of said wheel blank, 50 a slidable carriage mounted on said bed, a pair of carriages rigidly yet adjustably mounted on said slidable carriage, a cutter formed as a single helical pinion mounted in each of said adjustable carriages, means for reciprocating said slidable carriage, means for imparting a rocking motion to said cutters, and means for driving said wheel blank and said cutters simultaneously.
8. In a machine for generating and cutting double helical or herring bone toothed 60 gear wheels, the combination of means for mounting and turning a wheel blank on its axis, a bed arranged lengthwise in a plane parallel with said axis, a slidable carriage 65 mounted on said bed, a pair of carriages

rigidly yet adjustably mounted on said slidable carriage, means for imparting a reciprocatory movement to said carriage, a cutter formed as a single helical pinion mounted in each of said adjustable carriages, means adapted to impart an intermittent feed motion to said cutters, and means for adjusting the relative position of the cutters on the slidable carriage with respect to each other and to the work being done.

9. In a machine for generating and cutting double helical or herring-bone toothed gear wheels, the combination of means for mounting and turning a wheel blank on its 80 axis, a bed arranged lengthwise in a plane parallel with said axis, a slidable carriage mounted on said bed, a pair of carriages rigidly yet adjustably mounted on said slidable carriage, a cutter formed as a single helical pinion mounted in each of said adjustable carriages, means adapted to turn both of said cutters in their carriages and a crank operatively connected to said slidable carriage for causing the same to slide 85 to and fro upon said bed and thereby reciprocate both of said cutters simultaneously in front of the periphery of said wheel blank.

10. In a machine for generating and cutting double helical or herring-bone toothed gear wheels, the combination of means for mounting and turning a wheel blank on its axis, a bed arranged lengthwise in a plane parallel with said axis, a slidable carriage 100 mounted on said bed, a pair of carriages rigidly yet adjustably mounted on said slidable carriage, a cutter formed as a single helical pinion mounted in each of said adjustable carriages, means adapted to axially 105 turn each of said cutters in its carriage, a crank operatively connected to said slidable carriage for causing the same to slide to and fro upon said bed and thereby reciprocate both of said cutters simultaneously in front 110 of the periphery of said wheel blank, means for regulating or adjusting the relative positions of the cutters on the slidable carriage with respect to each other and to the work being done and means for varying the throw 115 of said crank and thereby the travel of the slidable carriage.

11. In a machine for generating and cutting double helical or herring-bone toothed gear wheels, the combination of means for 120 mounting and turning a wheel blank on its axis, a bed arranged lengthwise in a plane parallel with said axis, a slidable carriage mounted on said bed, a pair of carriages rigidly yet adjustably mounted on said slidable carriage, means for imparting a reciprocatory movement to said slidable carriage, a cutter formed as a single helical pinion mounted in each of said adjustable carriages, means adapted to impart an inter- 125 130

mittent feed motion to said cutters, means
for adjusting the relative positions of said
cutters on the slideable carriage with respect
to each other and to the work being done
5 and for throwing one cutter out of opera-
tion.

In witness whereof I have hereunto set

my hand in the presence of two subscribing
witnesses.

WILLIAM EDWIN SYKES.
